US0D1027438S

(12) **United States Design Patent** (10) Patent No.: **US D1,027,438 S**
(45) Date of Patent: ** May 21, 2024

(54) **GOLF BALL DISPENSER**

(71) Applicant: **Topgolf International, Inc.**, Dallas, TX (US)

(72) Inventors: **Brian David Burdette**, McKinney, TX (US); **Andrew David Macaulay**, Dallas, TX (US); **Clinton Scott Lovejoy**, Dallas, TX (US); **William Kevin Miner**, Frisco, TX (US); **Theodore YuChiang Cheng**, San Francisco, CA (US); **Mark Joseph Semsak**, Des Plaines, IL (US); **Gabriel Heath Denk**, Wylie, TX (US); **Justin Dean Pendleton**, The Colony, TX (US); **Brian Lee Roderman**, Plano, TX (US); **David Christopher Singer**, Austin, TX (US); **Clifton Frederick Geisler**, McKinney, TX (US); **Scott Michael Thibeault**, Redwood City, CA (US); **Frances Meng Wang**, San Francisco, CA (US)

(73) Assignee: **Topgolf International, Inc.**, Dallas, TX (US)

(**) Term: **15 Years**

(21) Appl. No.: **29/706,400**

(22) Filed: **Sep. 19, 2019**

(51) LOC (14) Cl. **21-02**

(52) U.S. Cl.

USPC **D21/796**; D3/254

(58) **Field of Classification Search**

USPC D21/789, 791, 796; D3/254, 257

(57) **CLAIM**

The ornamental design for a golf ball dispenser, substantially as shown and described.

DESCRIPTION

FIG. 1 is a perspective view of the golf ball dispenser.

FIG. 2 is a front view of the golf ball dispenser.

FIG. 3 is a back view of the golf ball dispenser.

FIG. 4 is a left side view of the golf ball dispenser.

FIG. 5 is a right side view of the golf ball dispenser.

FIG. 6 is a top view of the golf ball dispenser; and,

FIG. 7 is a bottom view of the golf ball dispenser.

The broken lines shown in the figures illustrate portions of the golf ball dispenser and form no part of the claimed design.

1 Claim, 7 Drawing Sheets
